STEEL WALER AND CLAMPING MEANS

Chester I. Williams, Grand Rapids, Mich.

Application September 8, 1950, Serial No. 183,736

13 Claims. (Cl. 25—131)

1

My invention relates to clamping and locking devices for concrete construction forms, and has among its objects the production of a simple and durable construction which will have a long life, and is adaptable for repeated uses.

The same has particularly as an object a form clamping device of great strength and rigidity, compact and usable with or without the studding generally used in form constructions.

The same has among its further objects a clamping device which may be readily and conveniently applied or removed.

A further object is a form clamping device of the kind described in which steel or like channel walers are used, preferably in pairs, as shown.

Another object is the production of a construction in which the walers may be conveniently and readily locked together on the form, and maintained in engagement with tie or form rods and form walls without the use of nuts, or like fastening members.

A further object is the production of a form clamping device in which the tie rods may be secured directly to the walers, maintaining the walers in secure assembly with the form sheathing and with one or more studding members, or without the studding.

Many other objects and advantages of the constructions herein shown and described will be obvious to those skilled in the art from the disclosure herein given.

To this end my invention consists in the novel construction, arrangement, and combination of parts herein shown and described, and more particularly pointed out in the claims.

In the drawings, wherein like reference characters indicate like or corresponding parts:

Fig. 1 is a sectional view through one side of a form taken substantially on line 1—1 of Fig. 2, and illustrating the use of a single studding;

Fig. 2 is a sectional view taken substantially on line 2—2 of Fig. 1;

Fig. 3 is a sectional view similar to Fig. 1, illustrating the omission of studding, taken substantially on line 3—3 of Fig. 4;

Fig. 4 is a sectional view taken substantially on line 4—4 of Fig. 3;

Fig. 5 is a view similar to Fig. 1 illustrating a modified form of means for securing the walers together, the same being taken substantially on the line 5—5 of Fig. 6;

Fig. 6 is a sectional view taken substantially on line 6—6 of Fig. 5; and

Fig. 7 is a view in elevation of a locking device shown in Figs. 5 and 6.

2

Referring to the drawings, and first to Figs. 1 and 2, in which only one side of the form is shown, it being understood, however, that while the opposite side is ordinarily the same as shown in Figs. 1 and 2, it may be modified without departing from the spirit of the invention, 1 represents sheathing, ordinarily of plywood boards, sheet metal, or their equivalents. A stud 2 is shown bearing against the sheathing, it also being understood that the studs may be in pairs. The walers are each preferably in two parts or pairs, such as steel channels having side flanges 4 arranged with the free edges of the flanges extending toward each other, but with a space 10 between. There is also shown a form tie rod 5 engaged by a tie rod extension 6, as for example, a screw threaded engagement. Any type of tie rod or extension and connecting means may be employed. The rod 6 extends through the sheathing 1 at each side and at the exterior of the form, and in between the walers 3. In the construction illustrated, the rod 6 is notched at each side, as indicated at 7, the flanges 4 of the two walers engaging in the notches, the waler, as shown in Fig. 2 bearing against the studding 2. To lock the walers 3 together, as well as to lock the form sheathing, tie rods and studding to the walers, a locking member 8 is provided adapted to engage the faces of the channeled walers. The particular locking member 8 shown, is flanged at 9 and apertured to permit the rod 6 to pass therethrough. The member 8 is shown locked on the tie rod 6 by means of a nail 10, or any equivalent for the purpose. The tie rods thus rigidly tie the two sides of the form together, and maintain the walers in engagement with the studding 2.

The construction in Figs. 3 and 4 is similar except that, as shown, the walers 3 bear directly against the sheathing 1, the studding being omitted. In some construction jobs it may be desirable to employ the studding, but in other jobs, the studding may be omitted and the walers maintained against the outer face of the sheathing. Obviously, studding may be employed at both sides of the form, as shown in Fig. 1, or without studding, as shown in Figs. 3 and 4, or with one side of the form arranged as shown in Fig. 1 with studding, and the other side of the form maintained without studding, as shown in Fig. 3.

In the construction shown in Figs. 5, 6 and 7, the locking member 8, shown in Figs. 1 to 4, is not employed, but in this case the walers 3 are maintained in assembled relation by bolts 11, or

their equivalents, connecting the channels 3. The bolts 11 are rigidly secured to one of the members 3 by nuts 12, it being obvious the same may be secured in any equivalent manner. Referring to the figures, a cam lever 13 is provided with a bifurcated end 14 embracing the end 11' of the bolt 11, the lever 13 and bolt 11 being secured together by means of rivets 15, or their equivalents. As shown in Fig. 7, the lever 13 is so designed that the cam 14 maintains the waler members or channels 3 firmly together, with the flanges 4 engaging in the notches 7 of the rod 6, securely locking the tie rods and form parts together. To release the same, the levers 13 are swung to move the cams away from the adjacent member 3, whereby the waler members 3 may be separated sufficiently to release the rods 6, permitting the removal of the rods 6 from the form and permitting the walers to be employed again on a form.

As in the constructions previously described, the studs may be employed or omitted, as desired, at one or both sides of the form. The construction shown in Figs. 5, 6 and 7 has an advantage over that shown in Figs. 1 to 4 in which figures the locking member 3 is employed, in that the walers and clamping means provide a unitary structure, it being unnecessary to remove the bolts and levers 13 when applying or removing the walers from the form.

Having thus described my invention, it is obvious that various immaterial modifications may be made in the same without departing from the spirit of my invention; hence, I do not wish to be understood as limiting myself to the exact form, construction, arrangement and combination of parts herein shown and described or uses mentioned.

What I claim as new and desire to secure by Letters Patent is:

1. A waler for construction forms consisting of two metal channel members spaced from each other and arranged with the free edges of the flanges on one waler member adjacent similar flanges on the adjacent waler member, a tie rod extending between the waler members and engaging therewith, means formed on the tie rod complementary to the flanges to receive the flanges of the oppositely arranged waler members, and means for clamping the channel members together with the rod disposed therebetween and in engagement with the flanges of said waler members.

2. A construction form consisting of sheathing and two metal channel members constituting walers spaced from each other and arranged with the free edges of the flanges on one waler member adjacent similar flanges on the adjacent waler member, a tie rod extending between the waler members and engaging therewith, notched means formed on the tie rod complementary to the flanges to receive the flanges of the oppositely arranged waler members, and means for clamping channel members together with the notched means of the tie rod disposed therebetween and in engagement with the flanges of said waler members.

3. In a construction form and in combination, two metal waler channel members spaced from each other and arranged with the free edges of the flanges on one member adjacent similar flanges on the adjacent member, a tie rod extending between the channel members and engaging with the flanges thereof, oppositely formed notches formed on the tie rod to receive the flanges of the channel members, and means for

securing the said channel members together with the rod disposed therebetween and the flanges of the channel members contiguous to each other.

4. In a construction form, securing and spacing means consisting of tie rods and walers, each waler consisting of two channel members arranged with the flanges at their side edges in opposed relation but spaced from each other, the rods comprising means complementally formed to the flanges to receive and to engage adjacent their outer ends with said flanges, and means for securing the rods and walers together at the exterior of the forms.

5. A construction form, securing means consisting of tie rods and walers, each waler consisting of two channel members arranged with the flanges at their side edges in opposed relation but spaced from each other, the rods comprising means complementally formed to the flanges to receive and to engage adjacent their outer ends with said flanges, and means for detachably and rigidly securing the rods and walers together at the exterior of the forms.

6. In a construction form having suitable sheathing, means consisting of waler rods and walers for securing the sheathing at the sides of the form together, each waler consisting of two channel shaped members arranged with the flanges at their side edges in opposed spaced relation, the rods comprising notched means adjacent their outer ends and complementally formed to engage with said side flanges of said channel shaped members, and means for securing the walers and rods together at the exterior of the forms.

7. In a construction form, and in combination, spaced sheathing members, walers at each side of the form at the exterior of the sheathing, and tie rods extending across the form to the walers, the walers at a side of the form consisting of channel shaped bars arranged in pairs, with the flanges at the sides of one bar extending toward the flanges on the other bar, said tie rods extending between the walers, said rods notched to receive and to engage the flanges on the oppositely arranged channels, and means for securing the waler members and tie rods together.

8. In a construction form, and in combination, spaced sheathing members, walers at each side of the form at the exterior of the sheathing, and tie rods extending across the form and connecting the walers, the walers each consisting of channel shaped bars arranged in pairs, with the flanges at the sides of one bar extending toward the flanges on the other bar, said tie rods extending between the walers at each side of the form, comprising notched means complementally formed to receive and engage the flanges of the channel-shaped bars, and means for locking the waler members and tie rods together.

9. In a construction form, and in combination, spaced sheathing members, studding and walers at each side of the form at the exterior of the form engaging with the studding, and tie rods extending across the form to the walers at each side of the form, the walers each consisting of channel shaped metal bars arranged in pairs, with the flanges at the sides of one bar extending toward the flanges on the other bar, notched tie rods extending between the walers and engaging at the notches with said flanges thereon, and means for locking the waler members and tie rods together.

10. The combination of a two part waler, a tie rod comprising axially spaced notches contiguous

to the outer end and extending between the two waler parts and directly engaging the same at the spaced notches, and means for locking the waler parts and rod together in assembled relation.

11. The combination with a waler for construction forms, said waler comprising oppositely arranged channel-shaped members with the flanges spaced from each other, of a form tie rod adapted to extend between and adapted to be engaged by said flanges, said tie rod comprising means complementally formed to the flanges to prevent axial movement of said tie rod when the flanges engage the tie rod, and clamping means operatively connected to the bases of said channel-shaped members for clamping the channel members together with the form tie rod clamped and disposed therebetween.

12. A waler construction for construction forms including a form tie rod comprising axially spaced grooves contiguous to the outer end thereof, said waler construction comprising oppositely arranged channel-shaped members with the flanges opposed and spaced apart to receive the form tie rod, and clamping means including a transverse member affixed to the base of one of the channel-shaped members and adapted to extend through the base of the other channel-shaped member, and operator-operated means comprising cam means operatively mounted on said transverse member and adapted to abut the base of the last-mentioned channel-shaped member, whereby as the clamping means is actuated with a tie rod arranged between the channel-shaped members

with the spaced grooves in juxtaposition to said flanges, the channel-shaped members are adapted to be detachably affixed to the form tie rod.

13. A waler construction for construction forms including a form tie rod comprising axially spaced grooves contiguous to the outer end thereof, said waler construction comprising oppositely arranged channel-shaped members with the flanges opposed and spaced apart to receive the form tie rod, and clamping means comprising a U-shaped member adapted to be detachably connected to the form tie rod, and said U-shaped member adapted to extend about and abut the bases of the channel-shaped members with the flanges thereof operatively engaging said complementally formed grooves, and securing means operatively connected to the tie rod and adapted to operatively engage said U-shaped member, whereby the channel-shaped members, tie rod and U-shaped member are detachably affixed.
